[57] CLAIM

The ornamental design for a display package for cap, as shown and described.

DESCRIPTION

FIG. 1 is a perspective view of a display package for cap showing my new design;

FIG. 2 is a front elevational view thereof;

FIG. 3 is a rear elevational view thereof;

FIG. 4 is a top plan view thereof;

FIG. 5 is a left side elevational view thereof, with the right side elevation being a mirror image;

FIG. 6 is a bottom plan view thereof;

FIG. 7 is a rear elevational view of a second embodiment thereof;

FIG. 8 is a top plan view of the embodiment of FIG. 7; FIG. 9 is a left side elevational view of the embodiment of FIG. 7, with the right side elevation being a mirror image;

FIG. 10 is a bottom plan view of the embodiment of FIG. 7;

FIG. 11 is a rear elevational view of a third embodiment thereof;

FIG. 12 is a top plan view of the embodiment of FIG. 11;

FIG. 13 is a left side elevational view of the embodiment of FIG. 11, with the right side elevation being a mirror image;

FIG. 14 is a bottom plan view of the embodiment of FIG. 11;

FIG. 15 is a rear elevational view of a fourth embodiment thereof;

FIG. 16 is a top plan view of the embodiment of FIG. 14;

FIG. 17 is a left side elevational view of the embodiment of FIG. 14, with the right side elevation being a mirror image; and,

FIG. 18 is a bottom plan view of the embodiment of FIG. 14.

The front elevations of the embodiments of FIGS. 7, 11, and 15 are identical to the front elevational view shown in FIG. 2 of the embodiment of FIGS. 1 through 6.
